UNITED STATES PATENT OFFICE.

MARTHA HALOWELL CONNOR, OF BALTIMORE, MARYLAND, ASSIGNOR TO THE TIN DECORATING COMPANY OF BALTIMORE, OF BALTIMORE, MARYLAND, A CORPORATION OF NEW JERSEY.

DESIGN FOR A TALCUM-TIN.

36,274.

Specification for Design. Patented Sept. 14, 1920.

Application filed June 21, 1920. Serial No. 390,659. Term of patent 14 years.

To all whom it may concern:

Be it known that I, MARTHA HALOWELL CONNOR, a citizen of the United States, residing in the city of Baltimore, State of Maryland, have invented a new, original, and ornamental Design for a Talcum-Tin, of which the following is a specification, reference being had to the accompanying drawing, forming a part thereof, wherein—

Fig. 2, is a top plan view of the same, and
Fig. 3, is a bottom plan view.

What I claim is:

The ornamental design for a talcum tin, as shown.

MARTHA HALOWELL CONNOR.
